Oscar Geiss

UNITED STATES PATENT OFFICE.

CHARLES SCHILLING, OF UNION HILL, NEW JERSEY.

PHOTOGRAPHIC ACCESSORY.

1,372,458.

Specification of Letters Patent. Patented Mar. 22, 1921.

Application filed May 29, 1919. Serial No. 300,676.

To all whom it may concern:

Be it known that I, CHARLES SCHILLING a citizen of Switzerland, residing at Union Hill, county of Hudson, and State of New Jersey, have invented certain new and useful Improvements in Photographic Accessories, of which the following is a specification.

This invention relates generally to photographic accessories having more particular reference to a device whereby the shutter of a camera may be automatically thrown to expose the sensitized plate or film.

The invention has broadly for an object to provide a device whereby anyone using a camera may set the shutter to operate automatically after a certain period of time to enable the user to position himself within the focus of the camera to be included in the picture.

A further object is to provide a device of this kind which is simple in construction and compact in form and of relatively small size, and which may be readily applied to ordinary types of cameras, and changed from one camera to another as desired.

For further comprehension of the invention, and of the objects and advantages thereof, reference will be had to the following description and accompanying drawings, and to the appended claims in which the various novel features of the invention are more particularly set forth.

Figure 1 of the drawings is a face view of a device constructed according to my invention.

Fig. 2 is a top side view thereof.

Fig. 3 is an enlarged rear view with the cover removed.

Fig. 4 is a side view with the cover in transverse section.

Fig. 5 is a detail transverse section on the line 5—5 of Fig. 3, omitting the braking device.

Fig. 6 is a horizontal section on the line 6—6 of Fig. 3.

As here shown my improved device comprises a circular face plate 1 which forms a frame or support for the operating parts, a flanged cover 2 co-operating with the plate 1 to form a casing.

Upon the plate 1 is fixed a guide block 3 having the face thereof which abuts against the plate 1 vertically grooved as at 4 to receive slidably a rack-bar 5 having its upper end bent horizontally back as at 6 and pro-

vided with a notch or recess 7. This rack bar has teeth 8 formed on one side thereof which mesh with a pinion 9 on a shaft 10 which extends through the plate 1 and block 3. Upon the outer end of the shaft 10 is fixed a handle 11 whereby it may be rotated.

Upon the rear of the block 3 is fixed a spring case 12 through which the shaft 10 also passes. A watch spring 13 is contained in this case and may be secured in the usual manner at one end to the case and at the other end to a hub 14 fixed on the shaft 10. The spring is so arranged that when shaft 10 is rotated by handle 11 in a direction to move the end 6 of the bar 5 out of the main casing a winding movement is imparted to the spring so that the latter will, when released, move bar 5 in an opposite direction.

Fixed to the rear end of shaft 10 is a ratchet wheel 16 which is engaged by a pawl 17 pivoted as at 18 to a gear 19 loose upon the shaft 10 adjacent the ratchet 16, a spring 20 pressing this pawl against the ratchet wheel. The gear 19 meshes with a pinion 21 forming one of a train of multiplying gears which here comprises the alternating gears and pinions 22, 23, 24 and 25 in addition to the gear 19 and pinion 21 just referred to, this train of gears being suitably carried between the block 3 and a frame strip 26 carried on posts 27 on the latter. The number of gears in the train and the number of propellers may be increased or decreased as desired or as convenient.

A fan 28 is carried by the last pinion, 25, of the train, a braking or retarding influence being thus placed on the shaft 10 when rotated under the action of spring 13. A pin 30, carried on an arm 31 pivoted as at 32 upon the front of the face plate 1, and projecting through a slot 33 in this face plate, may be moved into and out of the path of travel of the fan, thus providing a releasable stop for holding the power mechanism against operation.

The present embodiment of the invention is adapted to operate with the well known plunger type of shutter throwing device which comprises a flanged member 35 on the end of a tube 36 and provided with a plunger 37.

In operation the handle 11 is turned to wind spring 13 and move bar 5 out, ratchet wheel 16 slipping under pawl 17 so that the winding, or setting, movement is effected independently of the braking device, the pin

so being moved into engagement with the fan 28. The device is then suspended from the member 35, the hooked end 6 of bar 5 straddling the latter and resting on the flanged 5 lower end thereof. In this position the bottom of the plunger 37 is adjacent the cover 2. Pin 30 is then swung away from fan 28 and the mechanism released causing the whole casing to be raised toward the end 6 of 10 the bar 5 and moving the plunger 37 inward. By reason of the retarding effect of the braking device an appreciable time will elapse before the plunger 37 moves sufficiently to throw the shutter, enabling the person manipulating the device to place himself within 15 the focus of the camera to be included in the photograph.

As will be apparent my improved device is easy to operate and may be carried around 20 without inconvenience, occupying no more space than an ordinary watch. Moreover since it does not require to be fastened in position it can be transferred without any trouble from one camera to another as desired.

Having thus described my invention, what 1 claim as new and desire to secure by Letters Patent, is:

1. A device of the class described comprising a casing, a grooved guide block secured upon one of the plates of the casing, a rotary shaft passing through and journaled in said casing, a pinion fast on said shaft, a ratchet fast on the inner end of said shaft, a gear 30 loose on said shaft, a watch spring, a case therefor, said spring having its ends secured 35 respectively to said case and to said shaft,

an operating bar slidably mounted in said groove and provided with a rack in mesh with said pinion, a retarding device, a train 40 of gears connecting said gear loose on said shaft with said retarding device, means for rotating said shaft in one direction to wind said spring and project said operating bar, and means for releasing said retarding device 45 to permit the spring to unwind to rotate said shaft in a reverse direction to retract said bar.

2. A device of the class described comprising a circular casing, a grooved guide block 50 secured upon the inner face of one of the casing plates, a rotary shaft passing through and journaled in said plate and guide block, a pinion fast on said shaft and extending into the groove in the guide block, a ratchet 55 fast on the inner end of said shaft, a gear loose on said shaft, a watch spring, a case therefor carried by said guide block, said spring having its ends respectively secured to said case and said shaft, an operating bar 60 slidably mounted in said groove and provided on one edge with a rack in mesh with said pinion, a retarding device, a train of gears connecting said gear loose on said shaft with said retarding device, means for 65 rotating said shaft in one direction to wind said spring and project said operating bar and means for releasing said retarding device to permit the spring to unwind to rotate said shaft in a reverse direction to retract 70 said bar.

In testimony whereof I have affixed my signature.

CHARLES SCHILLING.
